UNITED STATES PATENT OFFICE.

LUTHER E. MORRISON, OF NEW YORK, N. Y., ASSIGNOR TO MERGENTHALER LINOTYPE COMPANY, A CORPORATION OF NEW YORK.

TYPE OR MATRICES.

1,088,439.

Specification of Letters Patent. Patented Feb. 24, 1914.

Application filed August 23, 1912. Serial No. 737,080.

To all whom it may concern:

Be it known that I, LUTHER E. MORRISON, a citizen of the United States, residing at New York, in the county of New York and 5 State of New York, have invented certain new and useful Improvements in Type or Matrices, of which the following is a specification, reference being had therein to the accompanying drawing.

10 My invention relates to typographical machines, such as linotype machines of the general organization represented in Letters Patent of the United States, No. 436,532, to O. Mergenthaler, wherein an assembled 15 line of matrices is presented by the first elevator in front of a slotted mold, which is advanced face-wise against the matrices to close the front of the slot, and then filled from the rear with molten metal to produce 20 a slug or linotype, on the edge of which the type characters are formed.

Ordinarily the characters stand in inverted position on the matrices, and it has been the general practice to have the characters 25 of different size, such as nonpareil, minion, etc., alined along their heads or tops, or in other words, matrices of all fonts had a common alining level at the tops of the characters. Under another system more recently 30 inaugurated, the matrices have a common alining level at the bases of the characters. Both kinds of matrices are adapted to be employed in the commercial linotype machine, although it is necessary that the first 35 elevator descend to different extents in the respective cases, as described for instance in Letters Patent of the United States to J. R. Rogers, No. 1,028,137.

My present invention comprises a matrix 40 formed with a plurality of characters, adapted for different modes of alinement, for instance one along its top, and another along its base. This principle is particularly applicable to double or Janus-faced 45 matrices, wherein the characters are located respectively on opposite edges, but may also be applied to matrices of other forms, as for instance, where the different characters are formed on the same edge, or on an adjustable member, so that either may be brought 50 into operative position at will.

In the accompanying drawing, I have shown my invention in preferred form and by way of example, and as applied to the 55 several styles of matrices already described.

However, many changes and variations may be made therein, and in its mode of application, which will still be comprised within its spirit. For instance, it may be similarly adapted to types or dies, as well as matrices. 60 Generally speaking, I desire it to be understood that I do not limit myself to any specific form or embodiment, except in so far as such limitations are specified in the 65 claims.

Referring to the drawing: Figure 1 is a side view of a Janus-faced matrix, having my invention applied thereto; Fig. 2 illustrates the edges of several such matrices; Fig. 3 is a similar view of the opposite edges, 70 thereof; and Figs. 4 and 5 illustrate other adaptations of my invention.

Figs. 1, 2 and 3 illustrate double or Janus-faced matrices of the ordinary kind, formed in their opposite edges with characters A 75 and A¹, either of which may be brought into operative position, and with projecting ears E, whereby the respective characters A and A¹ are alined in relation to the mold, all in the manner well understood in the art. Referring to the matrices X¹, X² and X³, shown in Fig. 2, it will be seen that the characters A in their edges are arranged and located so as to be alined along their tops; whereas, the characters A¹ in their opposite edges, shown in Fig. 3, are arranged and located so as to be alined along their bases. In other words, each matrix is formed with a plurality of characters, one 80 designed for alinement at its base, and the other designed for alinement at its top. 85

As previously indicated, when different sets of matrices are employed in the same machine, one set with characters for top alinement, and the other set with characters 90 for base alinement, it has been necessary to cause the descent of the first elevator to different extents in the respective cases. Another result of my invention is to dispense 95 with this necessity, and to that end I may form the characters A and A¹ at different vertical heights on the matrix, (see Fig. 1), and in such manner that the elevator may descend always to the same point, the former variation in its position being now compensated for by the difference in location of the characters on the matrix. It will be understood that in all cases will be employed 100 molds of suitable size and location to cooperate with the respective characters. 105

Fig. 4 illustrates a modification, wherein the matrix Y is formed with characters B and B¹ in the same edge, one of them designed for top alinement, and the other for base alinement. Fig. 5 shows another adaptation, wherein the matrix Z is provided with an adjustable member Z¹, formed with the characters C and C¹, either of which may be brought into operative position at will, and one adapted for top alinement and the other for base alinement.

As previously stated, I have shown my invention only in preferred form and by way of example, and as applied to the specific matrices described, but obviously many alterations and modifications therein, and in its mode of application, will suggest themselves to those skilled in the art without departure from its scope.

Having thus described my invention, its construction and mode of operation, what I claim and desire to secure by Letters Patent of the United States is as follows:

1. A type or matrix formed with several characters, one character designed for alinement at its top and another designed for alinement at its base.

2. A type or matrix having characters on its opposite edges, that character on one edge designed for alinement at its top, and that on the opposite edge designed for alinement at its base.

3. A type or matrix having characters on its opposite edges, that character on one edge designed for alinement at its top and that on the opposite edge designed for alinement at its base, said characters being differently located on the respective edges, for the purpose described.

4. A series of type or matrices provided

with several sets of characters, these characters of one set designed to aline with each other at their tops, and those of another set designed to aline with each other at their bases.

5. A series of type or matrices provided on one edge with characters designed for alinement with each other at their tops, and provided on the opposite edge with characters designed for alinement with each other at their bases.

6. A type or matrix having characters on its opposite edges, that character on one edge designed for alinement at its top and that on the opposite edge designed for alinement at its base, said characters being located in different vertical positions on the respective edges, for the purpose described.

7. A series of type or matrices provided with several sets of characters, those characters of one set designed to aline with each other at their tops, and those of another set designed to aline with each other at their bases, and the several sets being located in different relative positions thereon.

8. A series of type or matrices provided with several sets of characters in their opposite edges, those characters of one set designed to aline with each other at their tops, and those of another set designed to aline with each other at their bases, and the several sets being located in different vertical positions on the respective edges.

In testimony whereof I have affixed my signature in presence of two witnesses.

LUTHER E. MORRISON.
